UNITED STATES PATENT OFFICE.

CLIFFORD F. KENDALL, OF STOCKTON, CALIFORNIA.

MILL-STOCK FEEDER.

SPECIFICATION forming part of Letters Patent No. 374,682, dated December 13, 1887.

Application filed January 6, 1887. Serial No. 223,625. (No model.)

To all whom it may concern:

Be it known that I, CLIFFORD F. KENDALL, of Stockton, San Joaquin county, State of California, have invented an Improvement in Mill-Stock Feeders; and I hereby declare the following to be a full, clear, and exact description of the same.

My invention relates to that class of devices used for feeding mill-stock of various kinds to rolls, purifiers, &c.; and my invention consists in the construction and combination of devices, which I shall hereinafter fully describe and claim.

The object of my invention is to provide a simple and effective mill-stock feeder.

Referring to the accompanying drawing for a more complete explanation of my invention, the figure is a vertical section of my mill-stock feeder.

20 A is the shell or housing of the feeder.

B is the box or hopper from which the mill-stock passes to the directing-chute C.

D is the receiver, into which the spout or chute directs the stock. The receiver, which 25 consists of an open-backed casing, is pivoted to and suspended by a bracket, E, at each end, which is itself adjustably secured to the housing of the feeder by means of the bolts e, passing through the elongated slots e', so that by 30 adjusting the bracket at each end the receiver may be set up accurately, as I shall hereinafter explain.

F is the rocker, consisting of a curved faced head, f, forming the rear wall of the receiver, 35 to which is attached the shank f', pivoted at f', and adapted to receive a vibratory motion on its pivotal center by means of the hanger f'', having at its upper end an eccentric-strap, f', fitted over an eccentric, f'', on the driving- 40 shaft f''. A spring, f'', connected with the end of the shank and with the frame above, holds the hanger to its position on the eccentric and prevents any lost motion. The curved head of the rocker is concentric with its pivot f' and fits within the open back of the receiver, 45 the lower edge or lip, d, of which bears by gravitation against the face of the rocker. In order to vary the degree or force of this contact or pressure, and consequently to regulate 50 the feed of the stock, I have secured to the lower front face of the receiver an arm, G, which carries a sliding weight, W, provided

with a set-screw, w, whereby said weight may be set at any given position on the arm, thereby changing the center of gravity of the receiver 55 and causing it to bear against the rocker with more or less force, so that the passage of the stock may be more or less retarded.

The face of the rocker is solid; but its surface is preferably roughened by a wire-netting 60 tacked to it for the purpose of rendering its action on the stock more certain as it feeds it down.

H is a shaking-table mounted under the rocker and receiver. It has a straight or level 65 portion, h, and an inclined portion, h'. It is secured at its upper end to the lower end of the rocker by means of a hinged joint, here shown as a flexible strap, h'', secured to each. The lower end of the shaking-table is connected 70 with a fixed block, I, by means of a hinged joint, such as is represented by the strap h'', secured to said block and to said table.

In the upper portion of the shaking-table, and directly under the feed-aperture through 75 which the stock passes, is a screen, J.

The operation of my feeder is as follows: The stock passes from the box or hopper B into the chute C, from which it is discharged into the receiver D. Its weight in the receiver 80 causes the separation of its lower edge, d, from the face of the rocker, thereby forming a feed-aperture through which the stock is forced by the vibrating rocker. It then falls onto the shaking-table, from which it is delivered to 85 the rolls or other machinery. The width of the feed-aperture is determined in the first instance by the amount of stock in the receiver, and the effect of the weight of the stock upon the width of the feed-aperture is accurately 90 adjusted and regulated by means of the sliding weight W upon the arm G, and which defines the ease of movement of said receiver under the weight of the stock therein. The adjustable brackets E are for the purpose of accurately adjusting the receiver at each end, so that its lower edge or lip, d, throughout its length shall bear against the rocker. The uneven or roughened face of the rocker, due to the attachment of the wire-netting, renders its 100 operation certain and effective. It will be seen that as said rocker moves through an arc of a circle it imparts no motion to the receiver, which remains steady against its face. The

vibratory motion of the rocker produces a corresponding vibration or rocking in the shaking-table H, which moves upon its lower hinge, h^3 , where it is connected with the fixed block. There is a great advantage in this particular movement and arrangement of the shaking-table, in that its motion all takes place about its lower or delivery edge as a center, so that where the stock passes off from the table to the rolls or other machinery it is not agitated, but flows along in a steady and even sheet. The stock dropping from the discharge-aperture between the rocker and receiver and falling upon the screen J in the shaking-table is sifted and broken up as to avoid all lumps. The vibratory movement of the table at its upper end causes the stock to spread out over its entire surface, and where it drops over the angle onto the inclined part h' it passes down in an even stream, being less agitated and less broken up as it approaches its discharge, at which point there is no motion of the table.

Having thus described my invention, what I claim as new, and desire to secure by Letters Patent, is—

1. In a mill-stock feeder, a feed-hopper and a swinging receiver having its back open and forming a pocket in communication with the feed-hopper, in combination with the curved faced vibrating rocker operating in the open back of the pocket and against its lower edge, substantially as herein described.
2. In a mill-stock feeder, the combination of the pivoted gravity-receiver D, into which the mill-stock is directed, the vibrating rocker F, operating in the open back of the receiver

and against the lower edge of said receiver, and the underlying vibrating table H, connected with and operated by the rocker, substantially as herein described.

3. In a mill-stock feeder, the pivoted gravity-receiver D, into which the mill-stock is directed, and the vibrating rocker F, operating against it, as described, in combination with the underlying shaking-table H, connected with the rocker at its upper or receiving end, and the block I, to which its lower end is secured, substantially as herein described.

4. In a mill-stock feeder, the pivoted gravity-receiver, into which the mill-stock is directed, and the vibrating rocker F, operating as described, in combination with the shaking-table H below, the flexible strap h^2 between the upper end of said table and the lower end of the rocker, the block I, and the flexible strap between the lower end of said table and said block, substantially as herein described.

5. In a mill-stock feeder, the pivoted gravity-receiver and the vibrating rocker operating in the open back of the receiver and against the lower edge, in combination with the block I, the shaking-table hinged at its upper end to the rocker and at its lower end to said block, and the screen J in said table, substantially as herein described.

In witness whereof I have hereunto set my hand.

CLIFFORD F. KENDALL.
